[57] CLAIM

The ornamental design for condiment shaker, as shown and described.

DESCRIPTION

FIG. 1 is a perspective view of a condiment shaker showing our new design;

FIG. 2 is a side elevational view, the remaining sides being identical;

FIG. 3 is a top plan view thereof; and,

FIG. 4 is a cross-sectional view taken along line 4—4 of FIG. 2.

The apertures are shown in broken lines for illustrative purposes only.
